TONE CONTROL SYSTEM

Lloyd J. Bobb, Glenside, Pa., assignor, by mesne assignments, to Philco Corporation, Philadelphia, Pa., a corporation of Pennsylvania

Application December 31, 1943, Serial No. 516,557

5 Claims. (Cl. 178—44)

1

This invention relates to tone control systems of the type particularly applicable to audio systems and has for an object the provision of a simple and inexpensive system by means of which the tone, or the bass and treble compensation, may be adjusted in conformity with the auditory characteristics of the human ear.

From one view point, an ideal audio frequency amplifier should have a response which is linear and level over the whole audio frequency range. While this is a desired electrical objective, it does not take into account the frequency response of the human ear nor, for that matter, the many variations introduced as the result of the inclusion in the circuits of devices having non-uniform frequency response characteristics such as loudspeakers and phonograph recording and reproducing elements. For example, in certain types of phonograph recording equipment, it is essential to limit the volume peaks to a degree which will prevent the driving of the recording stylus from one groove into or across the next adjacent groove. This means that if the drums, or bass notes, predominate they must be recorded at a volume level materially less than their actual level. It follows that when such a recording is reproduced it is highly desirable to restore the bass notes to their original volume in order that the tone reproduction may be of the desired high fidelity.

In addition to the foregoing, it is well understood that if the volume be decreased, there is a more rapid apparent loss of the frequencies at either end of the audible frequency spectrum as compared with the intermediate frequencies; that is the ear, with decreasing volume, requires higher relative energy for the high and low notes than for those in between. This means that the most satisfactory tone control should be capable of operation correspondingly to increase the bass and treble response without materially disturbing the amplitude of the tones in between.

In carrying out the present invention in one form thereof, a tone control system is provided in which the range of frequencies at each end of the audible spectrum may be increased in amplitude by amounts which generally conform with the response of the human ear.

The invention is characterized by the provision of a novel tone compensating network adapted for insertion in an audio system and having a series and shunt branches. A variable and a normally fixed resistor are included in both the series and shunt branches of the tone compensating network. The values of these resistors

2

bear a relation one to the other to provide a voltage division independent of simultaneous variation in the same direction of the variable resistors. This means that so far as the resistance network is concerned the output voltage remains substantially constant regardless of the setting of the variable resistors, whereas the impedance of the tone compensating network may be changed over a relatively wide range to produce the desired tone control.

For a more detailed explanation of the invention, and for further objects and advantages thereof, reference is to be had to the following description taken in conjunction with the accompanying drawing, in which:

Fig. 1 is a wiring diagram of a typical embodiment of the invention; and

Figs. 2 and 3 are graphs explanatory of the manner in which one feature of the system affects operation.

Referring to the drawing, the invention in one form comprises a network connected between the output circuit of the audio amplifier tube 15 and the output terminals 12 and 13. The tube 15 preferably has a relatively low plate resistance. Since the portion of Fig. 1 including tube 15 is conventional, detailed description of this portion is unnecessary.

In one embodiment of the invention the plate resistance of the triode 15 amounted to 7700 ohms while the resistor 20 had a value of around 50,000 ohms. The output from the tube 15 is applied, by way of a coupling capacitor 22, to the tone compensating network. In accordance with the embodiment shown in the drawing, this network comprises a series branch including a fixed resistor R₁ and a variable resistor R₂, and a shunt branch including a variable resistor R₃, fixed resistor R₄ and a capacitor C₁. The resistors R₁ and R₂ may be shunted by capacitors C₂ and C₃, respectively, for purposes hereinafter described. The input signal to the network, voltage E_p, may be applied between the left hand terminal of resistor R₁ and ground, while the output voltage E_o

is obtained from terminals 12 and 13 connected respectively to the junction of variable resistors R₂ and R₃ and to ground. The variable resistors R₂ and R₃ are preferably mounted on the same shaft and in any event the resistances thereof are varied simultaneously and in the same direction. This means that when R₃ equals 0, R₂ equals 0; and when R₂ is a maximum R₃ is a maximum. The fixed resistors R₁ and R₄ may have the same resistance values although it is preferred that R₁ be relatively high with respect to R₄ and

with respect to the plate resistance of triode 15 and further, that R_1 and R_4 bear a predetermined ratio one to the other. The ratio of R_2 with respect to R_3 is then made the same as the ratio of R_1 with respect to R_4 . In one modification of the invention the resistors R_1 to R_4 , inclusive, respectively had resistance values of 100,000 ohms, 1 megohm, 100,000 ohms and 10,000 ohms. In the absence of the condensers C_1 , C_2 and C_3 , the output voltage E_0 across the terminals 12 and 13 is then determined by the ratio of the resistance (R_1 , R_2) in the series branch to the resistance (R_3 , R_4) in the shunt branch. Therefore, if the resistance of R_2 and R_3 be varied in the same direction the voltage division between the two branches will be constant and independent of the settings of R_2 and R_3 . In other words the ratio

$$\frac{R_1+R_2}{R_3+R_4}$$

will always be the same and with the values used, by way of illustration, this ratio will always be equal to 10.

The foregoing neglects the capacitive reactance of the capacitor C_1 . The stated ratio, however, is closely approximated so long as the capacitive reactance or the impedance of the capacitor C_1 is small compared to R_3 and R_4 . The capacity of C_1 is, therefore, selected to give the above-stated condition above the range of, say 800 to 1000 cycles per second. Below this range, the impedance of the capacitor C_1 rises rapidly with decreasing frequency, and produces a corresponding increase in the magnitude of the output voltage E_0 for low frequencies only. The capacitor C_1 may be selected so that at the low frequency end of the desired band, and with R_2 and R_3 adjusted to their minimum resistance values, E_0 is not substantially less than the input voltage E_p which is applied to the tone compensating network. When the resistance of R_2 and R_3 is reduced to zero, it will be understood that the effect of the variation of impedance of capacitor C_1 with frequency will cause a correspondingly greater increase in the output voltage E_0 than in the case when R_2 and R_3 are maximum. This follows since the impedance of the capacitor C_1 at the lower frequencies will then be larger as compared to the sum of R_3 and R_4 .

With the resistance values suggested above, it follows that the ratio of R_3 plus R_4 to the impedance of the capacitor C_1 can be made to vary by a factor of 11 by adjustment of resistor R_3 . Thus the rise in the output voltage E_0 due to rise in impedance of the capacitor C_1 at low frequencies may be controlled. With a capacity C_1 of 0.03 microfarad the bass rise may be around 1.25 decibels at 80 cycles with R_2+R_3 a maximum. However when R_2+R_3 are a minimum, or equal to zero, the bass rise at 80 cycles will be around 15 decibels. The range of corrections provided by an increase in the bass response from 1.25 decibels to around 15 decibels is adequate not only to compensate for a frequency distorting device included in the circuit, but it is also adequate to emphasize the bass notes or tones to conform with the desires of those who like the low frequency end of the sound spectrum emphasized.

If it is desired to provide even greater bass emphasis, the condenser C_1 may be shunted by an inductance of such magnitude as to produce shunt resonance at the low frequency end of the band.

The capacitors C_2 and C_3 , respectively, shunting the resistor R_1 and R_2 serve to emphasize the notes at the upper, or high frequency, end of the audible spectrum. Without the capacitors C_2 and C_3 , the effect of the distributed capacitance between the leads, and between the grid and cathode of the amplifier stage connected to the terminals 12 and 13, is to reduce or attenuate the high frequency sounds. This distributed capacity, lumped together, is indicated by the capacitor C_4 . When the resistors R_2 and R_3 are a maximum the capacitor C_4 is most effective in attenuating the high frequencies. The response may, for example, be reduced as indicated by the curve 25. However, by including the capacitors C_2 and C_3 the attenuation of the high frequencies is effectively eliminated and a response as indicated by the curve 26 may be obtained.

With the resistors R_2 and R_3 at a minimum, corresponding to a maximum bass response, it will be understood that the effect of the capacitor C_4 in attenuating the higher frequencies is a minimum. In other words, the impedance of the system looking back from the terminals 12 and 13 is a minimum. In this case the capacitor C_2 emphasizes the higher frequencies. It serves to increase E_0 at the higher frequencies. In a typical embodiment of the invention the capacitor C_2 had a capacitance of 400 micromicrofarads while the capacitor C_3 had a capacity of 50 micromicrofarads. Preferably the same ratio, around 10 to 1, is maintained between the capacitors C_2 and C_3 as between the resistors R_1 and R_2 , so that when R_2 is maximum the time constant of the circuit R_1-C_2 is the same as the time constant of the circuit R_2-C_3 .

With R_2 and R_3 adjusted to their minimum values, and without the capacitors C_2 and C_3 , the frequency response would be as indicated by the curve 27 of Fig. 3, but with the capacitors the gain or emphasis thereof is indicated by the curve 28.

With a properly designed amplifier, the over-all response with the tone control set for minimum compensation is indicated by the curve 26 which it will be observed is linear over the full range of the audible frequency spectrum except for a slight emphasis at the very low frequencies.

However, the tone control set for maximum compensation, the over-all response curve 28 shows the substantial emphasis of the sounds of low frequency as well as the substantial emphasis of the sounds at the higher frequencies. Sounds at the intermediate frequencies are emphasized to a much lesser degree. This not only makes it possible to select a tone control position such that compensation of the bass notes, needed because of their suppression during recording, is effective, but it also provides ideal compensation for operation of the system at low sound levels. The compensation is adequate to produce esthetic effects by overemphasis.

As the volume is decreased, the sounds to which the ear first fails to respond are those at the ends of the sound frequency spectrum. That is one reason why in relatively inexpensive radio receivers, the quality is poor when the volume is low. In accordance with the present invention, the tone control on such receivers may be set for maximum compensation and the volume then reduced to a very great degree without material loss of quality. The emphasis of highs and lows indicated by the curve 28 ideally compensates for the lack of response of the ear. The

quality or fidelity of reproduction of music having an abundance of highs and lows remains the same even though the volume has been greatly reduced.

The present invention has the further advantage of low cost. The required circuit elements are relatively inexpensive and the testing and adjustment of the circuits during manufacture is simple.

I claim:

1. In a tone control system including an electric valve having a relatively low output impedance and an output circuit for said valve, the combination of a fixed resistor having a resistance relatively high as compared with the plate resistance of said valve, a variable resistor having a resistance approximately ten times that of said fixed resistor, means connecting said two resistors in series in said output circuit, capacitors connected across said fixed and variable resistors and having capacities whose ratio is approximately 10 to 1, a second fixed resistor and a second variable resistor in circuit with said first-named resistors and respectively having resistance values which differ in the order of 10 to 1, a capacitor connected in series with said second fixed and said second variable resistor, an output circuit connected across said second fixed resistor, said second variable resistor and said last-mentioned capacitor, and means for simultaneously varying the resistance of said variable resistors in the same direction such that when the resistance of one is a minimum the resistance of the other is a minimum thereby to control the effectiveness of said last-mentioned capacitor in producing emphasis of frequencies in the lower range of the audible frequency spectrum.

2. An audio frequency control network including a series branch having a pair of series-connected resistors therein and a capacitor in shunt with each resistor, a shunt branch having a pair of resistors and a capacitor serially connected therein, said shunt branch being connected to the output end of said series branch, and means for simultaneously varying one of said series branch resistors and one of said shunt branch resistors in the same direction.

3. A tone control network for the audio frequency range, said network having series and shunt branches, said series branch comprising a variable resistive impedance and a capacitive impedance connected in shunt thereacross, said shunt branch comprising a variable resistive impedance and a capacitive impedance connected in series therewith; means for deriving an output voltage across said shunt branch; and means for varying said variable resistive impedances in both branches simultaneously in the same direction, the values of said resistive impedances and the relative rates of variation thereof being such

that the ratio of the total resistive impedance of said shunt branch to the total resistive impedance of said network remains substantially constant irrespective of the setting of the variable means,

5 5 the ratio of the capacitive impedance of said shunt branch to the combined capacitive and resistive impedances of said network at a given frequency being variable and dependent upon the setting of said variable means, whereby said out-

10 put voltage at both the low and high frequency ends of the audio frequency range varies appreciably in accordance with the setting of said variable means, said output voltage at the intermediate audio frequencies remaining relatively constant irrespective of the setting of said variable means.

4. A tone control network for the audio frequency range, said network having series and shunt branches each including resistive imped-
20 ances adapted to be varied from a maximum to a minimum value, said minimum value being larger than zero, the ratio between said maximum values of the two branches being substantially equal to the ratio between said minimum values, said se-
25 ries branch having capacitive impedance in shunt with said resistive impedance, said shunt branch having capacitive impedance in series with said resistive impedance; means for deriving an out-
30 put voltage across said shunt branch; and means for varying the resistive impedances of both branches simultaneously in the same direction at such relative rates that the ratio of the instantaneous resistive impedance of the series branch to that of the shunt branch is maintained substan-
35 tially equal to said first-mentioned ratio, whereby said output voltage at both the low and high frequency ends of the audio frequency range varies appreciably in accordance with the setting of said variable means, said output voltage at the inter-
40 mediate frequencies remaining relatively constant irrespective of the setting of said variable means.

5. A tone control network as claimed in claim 4 characterized in that the output voltages at the low and high frequency ends of said audio frequency range are increased as said resistive impedances are varied toward said minimum values.
